INTERNAL-COMBUSTION ENGINE.

1,215,870.

Specification of Letters Patent. Patented Feb. 13, 1917.

Application filed October 4, 1911. Serial No. 652,776.

To all whom it may concern:

Be it known that I, ADOLPH ROSNER, a subject of the Emperor of Austria-Hungary, and a resident of Bridgeport, in the county of Fairfield and State of Connecticut, have invented an Improvement in Internal-Combustion Engines, of which the following description, in connection with the accompanying drawings, is a specification, like characters on the drawings representing like parts.

This invention relates to internal combustion engines and particularly to the means for controlling the admission of fuel to the cylinder and the exhaust of the waste gases therefrom.

In carrying out my invention I preferably make use of slide valves. The valves as herein disclosed, however, are so designed and disposed that an extremely high degree of compression can be readily attained, while, at the same time, the valves are simple in construction and operation and are free from the difficulties of lubrication, overheating and other troubles to which valves of this class have heretofore been subjected.

The invention will be best understood by reference to the following description when taken in connection with the accompanying illustration of one specific embodiment thereof, while its scope will be more particularly pointed out in the appended claims.

In the drawings:

Figure 1 is a transverse sectional elevation taken through the cylinder of a multiple cylinder engine equipped with one form of my invention; and

Figs. 2, 3, 4 and 5 are sectional elevations partly diagrammatic showing the piston and valves in different positions.

Referring to the drawings, and particularly to the embodiment of the invention shown in Fig. 1, the engine there illustrated is provided with a fixed main cylinder 1 supported upon the crank casing 2 and having the working piston 3 connected by the connecting rod 4, to the crank 5 and crank shaft 6. The working space of the cylinder or that through which the piston travels is surrounded by the water jacket 7 and the piston slides in direct contact with the water jacketed walls of the fixed cylinder. The rear end of the cylinder is closed by the cylinder head 8 which is bolted or other-

wise fixedly secured to the head end of the cylinder, forming a gas tight joint and a gas tight closure for the cylinder end. The cylinder head has a portion which projects into the rear end of the cylinder, the extreme end thereof at 9 preferably fitting closely the walls of the cylinder and terminating just beyond the rearward limit of piston travel. A portion of the projecting part of the cylinder head is of lesser diameter than the interior of the cylinder so that there is provided an annular space 10 between the cylinder and the reentrant walls of the head. The cylinder head has the centrally arranged spark plug 11 and is provided with the water jacket 12.

At the rear of the cylinder beyond the working space thereof and where the same is overlapped by the projecting portion of the head, there are provided one or more ports, the disclosed embodiment of the invention having the oppositely interposed admission and exhaust ports 13 and 14, respectively. As shown in Fig. 1 these are arranged to coöperate and preferably in registration with similar ports 15 and 16 in the projecting portion of the cylinder head. As shown in Fig. 1, both sets of ports extend part way around the cylinder, the cylinder admission port communicating with an admission space 17 and supply pipe (the latter not shown) and the cylinder exhaust port with an exhaust space 18 and exhaust pipe (the latter not shown).

In the described embodiment of the invention communication with the working space of the cylinder and the admission and exhaust spaces through the described admission and exhaust ports, respectively, is controlled by independently movable slide valves 19 and 20, respectively. While the valves may consist of flat plates or have other than curvilinear shape, for convenience in construction, as well as for efficient operation, each valve preferably comprises an arc-shaped, but non-cylindrical, segmental plate having a curvature corresponding to the curvature of the cylinder bore so that it is adapted to seat thereagainst and longitudinally movable in the annular space 10.

These valve plates or slides are moved independently by means to be later described so that when moved back into the annular space 10, communication is opened between the adjacent ports 13 and 15 or 14 and 16

as the case may be, but when moved in the opposite direction the forward end of the slide is interposed between the ports 13 and 15, or 14 and 16, cutting off communication between the respective interior and exterior ports.

To move the valves independently and in properly timed relation, actuating devices are provided having connection with the valves through openings 21 and 22, formed in the cylinder walls and in the seat over which the valves slide. In the openings 21 and 22 there are pivoted the actuating levers 23 and 24, respectively. These are connected to the valves at their outer sides or faces, each by means of a trunnion block 25 seated between lugs 26 projecting outwardly from the valves, the block being spanned by and jointed to the forked ends of the lever.

To actuate the valves the levers 23 and 24 are jointed respectively to the push rods 27 and 28, the latter being connected at their lower ends to the cam rolls 29 and 30 which bear respectively against the actuating cams 31 and 32 on the cam shafts 33 and 34. These cam shafts are driven through gears 35 and 36 meshing with the pinion 37 on the crank shaft at one-half the speed of the crank shaft. Each cam is provided with one depression which when brought beneath the cam roll permits its respective valve to move back into the annular space 10 and open its respective port under the pressure of a valve opening spring, such opening movement therefore taking place once for each two double strokes of the piston.

In the illustrated form of engine the spring pressure is provided by the main springs 38 and 39 which encircle the push rods 27 and 28 and press the cam rolls down against the edges of the cams 31 and 32. The push rods and associated parts are housed in by the protective casings 40 and 41. To supplement the pressure of the springs 38 and 39 as well as to take up lost motion in the actuating connections of the valves, auxiliary springs 42 and 43 are utilized to assist in opening the valves. These springs are seated exteriorly in the cylinder head 8 being connected by the caps 44 and 45. Each spring is under compression and presses upwardly against a collar 46 carried by the plunger rod 47, the latter passing through the flange of the cylinder head and having its opposite end threaded to one of the lugs 26. When the depression of the cam passes under the cam roll, the auxiliary spring adds its pressure to that of the spring 38 and assists in lifting the valve to an open position.

It will be seen that a part of the inner face of each valve when it is in its closed position is exposed to the pressure of the gas contained in the cylinder through the

cylinder head port 15 or 16, and the valve is thereby automatically seated during the compression and working strokes of the piston through the high pressure exerted radially outward which tends to hold each valve effectively against its seat. The resistance of the valve to leakage is thereby automatically increased as the pressure of compression or during the working stroke increases. The valves are preferably housed in by the cylinder head and protected against the intense pressure except where exposed through the ports 15 and 16. As shown in the illustrated embodiment moreover to further exclude unnecessary pressure from the inner faces of the valves they are preferably each in the form of a half sleeve with the ends meeting and are given a close fit in the annular space 10. Preferably spring rings 48 and 49 constituting packing rings are provided in the walls of the cylinder head between the latter and the inner faces of the valves so that leakage of high pressure fluid to the inner faces of the valves or the rear end of the annular space 10 is prevented. These rings also assist in seating the valves against the walls of the cylinder. The upper end of the annular space 10 may be vented by one or more longitudinal grooves 50 in the outer faces of the valve segments 19 and 20.

At the beginning of the suction stroke before the admission valve is opened or opened fully, a slight vacuum may be formed in the working space of the cylinder and this tends to lift or unseat the valves 19 and 20. By causing the projecting end of the cylinder head to overlap the inner face of the valve below the cylinder ports 13 and 14, a fixed overlapping wall 105 is provided for the inner face of each valve on each side of the fixed cylinder ports so that any tendency to lift from the seat is effectually prevented. The overlapping end 9 of the cylinder head also preferably, though not necessarily, fits closely the inner wall of the cylinder so as to protect both the end of each valve as well as its inner face from the heat and pressure of the cylinder working space.

Referring to Figs. 2 to 5, inclusive, the operation of the valves will be readily apparent. In Fig. 2 the piston is shown during its admission or suction stroke, the admission valve 19 having been retracted into the annular space and having opened the admission port 13 to the cylinder. The exhaust valve has been previously closed and is still maintained closed by its cam 32.

The conditions which pertain during the compression stroke are represented in Fig. 3. The piston is here shown as having started on the compression stroke, the admission valve 19 having been previously closed by its cam 31 and the exhaust valve 130

being still maintained closed by its cam 32. Under these conditions the increasing compression within the cylinder increasingly presses the valves against their respective seats so that as the compression increases, so also does the resistance to leakage at and about the valves.

5 In Fig. 4 the conditions at the commencement of the working stroke are represented, the piston having started on its second forward movement and both valves being still maintained closed by its respective cam.

10 In Fig. 5 the piston is shown as having completed its working stroke and as starting on the return or exhaust stroke, the exhaust valve 20 having been permitted to open by its cam at the commencement of the stroke.

15 The valves may be given a very short stroke, herein the equivalent only of the port opening plus the necessary lap, and through the use of the cams as actuating agents may be moved each at such an appropriate time as gives the most effectively timed port

20 opening for the admission and exhaust. Thus, during suction stroke, the admission valve can be opened almost instantly after the commencement of the admission stroke and remain open until a little after the completion of the stroke.

25 On the other hand, the exhaust valve may be opened near the very close of the working stroke and can be kept open until the completion of the exhaust stroke of the piston. By modifying the shape of the cams the precise timing of the valves can be independently varied as may be desired and preferably I so set the cams that the exhaust valve is not closed until a few degrees after the completion of

30 the exhaust stroke of the piston and not until the admission valve has started to open, so that there is a slight interval during which both valves are opened permitting a momentary scavenging action.

35 The opening and closing movements of the valves in each case are effected very rapidly by means of the cams. This adds materially to the effectiveness of the admission, compression, working, and exhaust strokes.

40 The cam-operated movement of the valves and the short travel required produces a minimum of wear. It will be observed moreover that the valves are only in motion when the internal pressure is slight, periods of 45 compression and firing occurring when the valves are stationary. This not only reduces the frictional wear of the valves but also the power required to move them and provides conditions which assist in preventing

50 leakage.

The valves as herein shown are preferably located at the rear of the working space of the cylinder and out of contact with the piston, this placing them out of the direct path of heat conduction or dispersion which

takes place from the working cylinder space through the cylinder walls to the water jacket. The slide valves therefore are not only themselves out of the direct path of heat which must be dissipated through the 70 cylinder walls and that intense heat which tends to interfere with their effective operation is avoided, but the cooling of the cylinder is much more effectively carried out where the heat does not have to traverse the 75 valves themselves interposed between the piston and the cylinder walls.

It will be observed that with the valves located having the major portion of each within the annular spaces between the cylinder head and the cylinder they are not only protected against the access of pressure to their inner faces but are shielded by the projecting cylinder head from the intense heat of the combustion chamber during the 80 working stroke, the only portions of the valves which are thus exposed being the portions uncovered by the cylinder head ports 15 and 16.

85 While the valves might be arranged upon 90 seats not constituting a part of the cylinder bore, preferably as herein shown they are seated in a continuation of the cylinder bore, being however in a non-concentric or non-overlapping relation to the piston.

95 It will be understood that the terms "front", "rear", "top" and "bottom" as applied to the engine and its cylinder are merely terms of description applied to the specific drawings herein annexed to facilitate a more ready understanding of them, and have no significance as applied to the generic principles of my invention, various embodiments of which may be made wherein in the relation of the parts thus referred to 100 105 may be reversed or variously altered.

While I prefer to have the walls of the cylinder head overlap both the admission and exhaust slide valves on both sides of the cylinder ports for the purpose of correcting 110 the tendency above referred to of the valves to lift or unseat at the commencement of the admission stroke, a construction might be employed wherein the exhaust valve only is overlapped by the said cylinder head, the 115 cylinder head on the opposite side of the cylinder where it overlaps the admission valve terminating short of the admission port. Such construction, as well as other numerous modifications unnecessary to mention, are intended to be covered by the 120 claims herein.

125 While I have herein shown and described for purposes of illustration one specific form of the invention, it is to be understood that the latter is not limited to the precise construction of features disclosed nor to the form or relative arrangements of parts nor to the particular type of engine described, but that extensive modifications may be 130

made in the illustrated embodiment of the invention without departing from the spirit thereof.

Claims:

5. 1. In an internal combustion engine, the combination with a cylinder of a piston, said cylinder having admission and exhaust ports, means for controlling said ports comprising a pair of arc-shaped segmental 65 plates controlling one the admission port and the other the exhaust port, and a cylinder head having a portion projecting into the cylinder and providing space between the head and the cylinder to receive the 70 10 plates, said head overlapping said plates on opposite sides of said cylinder port.
2. In an internal combustion engine, the combination with a cylinder of a piston, a cylinder head, said cylinder having admission and exhaust ports and said cylinder head having ports in registration with said cylinder ports, means for controlling said 75 15 ports comprising a pair of arc-shaped, segmental plates controlling one the admission port and the other the exhaust port, and means for moving said plates to open or close said cylinder ports.
3. In an internal combustion engine, the combination with a cylinder having admission and exhaust ports, a cylinder head, a pair of arc-shaped slide valves working in the space between the head and the cylinder and controlling one the admission port and the other the exhaust port, and having 80 20 each a portion adapted to be advanced to cover the cylinder port controlled thereby, the forward end of the cylinder head overlapping said valve and fitting the cylinder walls thereat to protect the end of the valve, 25 25 said cylinder head also having a pair of ports, and means for moving the valve.
4. In an internal combustion engine, the combination with a fixed cylinder, admission and exhaust ports therein, a piston, a pair of arc-shaped, segmental slide valves wholly at the rear of the piston and controlling one the admission port and the other the exhaust port, and a fixed member in engagement with the inner face of said 85 30 slide valves and providing a wall overlapping said valves on opposite sides of said cylinder ports.
5. In an internal combustion engine, the combination with a fixed cylinder, admission and exhaust ports therein, a piston, a pair of arc-shaped, segmental slide valves wholly at the rear of the piston and controlling one the admission port and the other the exhaust port, and a fixed member in engagement with the inner faces of said 90 35 slide valves and providing a ported wall overlapping said valves on opposite sides of said cylinder ports.
6. In an internal combustion engine, the combination with a cylinder having admission and exhaust ports, a cylinder head, cooperating ports therein, a piston, and a pair of arc-shaped slide valves controlling communication between said cylinder and cylinder head ports, one slide valve controlling the admission ports and the other the exhaust ports and working in a space between said head and said cylinder, said valves being each protected by said head from the pressure of the working space of the engine except where exposed through the cylinder head port controlled thereby. 95 40
7. In an internal combustion engine, the combination with a piston of a cylinder having admission and exhaust ports located beyond the rearward limit of the piston travel, a cylinder head having a portion projecting into the cylinder and closely fitting the same beyond the cylinder ports, said cylinder head having ports to cooperate with said cylinder ports and having also an annular space between the same and the cylinder at the rear of said closely fitting portion, a pair of arc-shaped segmental slide valves located in said annular space and controlling separately said ignition and exhaust ports, and means for independently moving said valves. 99 45
8. An internal combustion engine comprising a fixed cylinder having admission and exhaust ports, a cylinder head having a portion separated therefrom by an annular space, a piston working in contact with said fixed cylinder, and segmental slide valves working wholly in said annular space between the cylinder head and the fixed cylinder and adapted to open and close said cylinder ports. 100 50
9. In an internal combustion engine, a stationary cylinder having laterally opening inlet and exhaust ports, a piston working within said cylinder in contact with the inner wall thereof, a removable head having a cylindrical portion projecting within the upper end of the cylinder, and provided with ports alining with the ports in the cylinder, and forming with the cylinder an annular chamber, means closing the lower end of said chamber to the combustion space of the cylinder, a pair of semi-cylindrical valve members located in said annular chamber, and means for operating said valves. 105 55
- In testimony whereof, I have signed my name to this specification, in the presence of two subscribing witnesses.

ADOLPH ROSNER.
